[57] CLAIM

The ornamental design for a lighter, as shown and described.

DESCRIPTION

FIG. 1 is a front view of a lighter;

FIG. 2 is a left-side view thereof;

FIG. 3 is a right-side view thereof;

FIG. 4 is a rear view thereof;

FIG. 5 is a top view thereof;

FIG. 6 is a bottom view thereof;

FIG. 7 is a front view of a lighter shown with the cap removed;

FIG. 8 is a right-side view thereof; and,

FIG. 9 is a perspective view thereof showing the lighter in an operative condition.

For the purpose of disclosure, the lighter is shown with the cap removed.
